CURLING ROD FOR PERMANENT WAVING

Filed May 2, 1932

UNITED STATES PATENT OFFICE

1,951,154

CURLING ROD FOR PERMANENT WAVING

Richard Klein, Detroit, Mich.

Application May 2, 1932, Serial No. 608,618

8 Claims. (Cl. 132—36)

My invention relates to a new and useful improvement in a curling rod for permanent waving and has for its object the provision of a curling rod structure which will be simple in structure, economical of manufacture, durable, highly efficient in use, and easily operated. Another object of the invention is the provision of a curling rod whereby the end thereof may be brought into close relation with the scalp and in which a burning of the scalp, either through direct contact or by escaping of steam, is prevented.

Another object of the invention is the provision of a curling rod of this class in which the various parts may be easily and quickly assembled.

Another object of the invention is the provision of a structure whereby the curling parts may be locked in position when the hair is wound upon the rod.

Another object of the invention is the provision of a structure for use in connection with a curling rod which will serve to provide a receptacle for the reception of any condensate which may be formed and which will serve as a guard against the escape of steam toward the scalp.

Another object of the invention is the provision of a pair of relatively movable hair locking parts which may be easily and quickly secured in position and which will always move to a pre-determined location so that the entry slots will be in alignment for the passage of a wisp of hair thereinto.

Fig. 1 is a perspective view of the rod and coupling discs used therein, the discs being shown in separate relation.

Fig. 2 is a perspective view of the rod with the discs used therewith the discs being in assembled relation.

Fig. 3 is a longitudinal sectional view of the invention.

Fig. 4 is a sectional view taken on line 4—4 of Fig. 3 showing the discs with the entry slots in alignment for the passage of a wisp of hair thereinto.

Fig. 5 is a view similar to Fig. 4 showing the discs rotated from the position shown in Fig. 4.

Fig. 6 is a view similar to Fig. 5 showing the winding member in operative position relatively to the wisp of hair.

Fig. 7 is a fragmentary view of the winding member similar to Fig. 6 but illustrating the same after the wisp of hair has been partly wound upon the rod.

Fig. 8 is a sectional view taken on line 8—8 of Fig. 3.

Fig. 9 is a fragmentary sectional view of the assembled cup shaped members.

In the invention I use a curling rod 12 which is secured to and projects centrally upwardly from the base of a cup-shaped member 13 having the upstanding inwardly inclined flange or side walls 14. A notch 15 is formed inwardly of this cup-shaped member terminating in an elongated slot. A cup-shaped member 17 is adapted to fit over the cup-shaped member 13. The upstanding flange or side wall 19 of the cup-shaped member 17 is also inclined. An opening or notch 18 is formed in the cup-shaped member 17 to conform to the contour of the opening or notch 15 and this opening or notch 18 terminates in an elongated slot 18' which is faced oppositely to the notch or slot 16. The member 17 is fastened on the member 13 solely by its frictional engagement therewith, the member 17 snapping onto the member 13 and to this end the member 17 must be made of metal sufficiently resilient for this purpose. When the parts are assembled in this manner, as shown in Fig. 2, and rotated relatively to each other until the pin 21 which projects downwardly from the base of the member 13 and which rides in the groove 20 formed in the upper surface of the base of the cup-shaped member 17 has reached the end of the groove the openings or notches 18 and 15 will be in alignment so that a wisp 45 of hair may be inserted into these openings. Thereupon, the disc or cup-shaped member 17 will be rotated relatively to the disc or cup-shaped member 13. In Fig. 4 these cup-shaped members are shown in alignment and the wisp 45 of hair has been moved into the space provided. In Fig. 5 a relative rotation of these members has been effected so that the wisp of hair engages in the slots 16 and 18' and it will be noted that the wisp of hair is shaped into arcuate form to partly embrace the curling rod 12. In order to lock these parts 13 and 17 in position to retain the wisp of hair and prevent any undue movement of the parts the set screw 22 carried by the flange 19 is threaded against the flange 14, which prevents relative rotation of the members 13 and 17. A cup-shaped retainer 40 is clamped about the disc 17 and secured to the outer surface of the base of the cup-shaped retainer 40, which is also provided with an inclined resilient wall 41, is a layer 42 of heat insulating material and a layer 43 also of heat insulating material but soft and yieldable such as a layer of felt, leather, or the like. This layer 43 will engage closely against the scalp and since there are no outward projections from the as-

sembled parts 13 and 17, the scalp will not be injured by the use of the invention.

Fig. 6 is a view similar to Fig. 5 showing the winding member in operative position relatively to the wisp of hair.

Fig. 7 is a fragmentary view of the winding member similar to Fig. 6 but illustrating the same after the wisp of hair has been partly wound upon the rod.

Fig. 8 is a sectional view taken on line 8—8 of Fig. 3.

Fig. 9 is a fragmentary sectional view of the assembled cup shaped members.

In the invention I use a curling rod 12 which is secured to and projects centrally upwardly from the base of a cup-shaped member 13 having the upstanding inwardly inclined flange or side walls 14. A notch 15 is formed inwardly of this cup-shaped member terminating in an elongated slot. A cup-shaped member 17 is adapted to fit over the cup-shaped member 13. The upstanding flange or side wall 19 of the cup-shaped member 17 is also inclined. An opening or notch 18 is formed in the cup-shaped member 17 to conform to the contour of the opening or notch 15 and this opening or notch 18 terminates in an elongated slot 18' which is faced oppositely to the notch or slot 16. The member 17 is fastened on the member 13 solely by its frictional engagement therewith, the member 17 snapping onto the member 13 and to this end the member 17 must be made of metal sufficiently resilient for this purpose. When the parts are assembled in this manner, as shown in Fig. 2, and rotated relatively to each other until the pin 21 which projects downwardly from the base of the member 13 and which rides in the groove 20 formed in the upper surface of the base of the cup-shaped member 17 has reached the end of the groove the openings or notches 18 and 15 will be in alignment so that a wisp 45 of hair may be inserted into these openings. Thereupon, the disc or cup-shaped member 17 will be rotated relatively to the disc or cup-shaped member 13. In Fig. 4 these cup-shaped members are shown in alignment and the wisp 45 of hair has been moved into the space provided. In Fig. 5 a relative rotation of these members has been effected so that the wisp of hair engages in the slots 16 and 18' and it will be noted that the wisp of hair is shaped into arcuate form to partly embrace the curling rod 12. In order to lock these parts 13 and 17 in position to retain the wisp of hair and prevent any undue movement of the parts the set screw 22 carried by the flange 19 is threaded against the flange 14, which prevents relative rotation of the members 13 and 17. A cup-shaped retainer 40 is clamped about the disc 17 and secured to the outer surface of the base of the cup-shaped retainer 40, which is also provided with an inclined resilient wall 41, is a layer 42 of heat insulating material and a layer 43 also of heat insulating material but soft and yieldable such as a layer of felt, leather, or the like. This layer 43 will engage closely against the scalp and since there are no outward projections from the as-

sembled parts 13 and 17, the scalp will not be injured by the use of the invention.

sembly the layer 43 may be brought into close engagement with the scalp. Where a number of these curling rods are used, and in giving a permanent wave a large number is always used, 5 the curling of the hair with each rod consequently is begun at a common distance from the scalp so that uniformity of the curl is possible and a more even and symmetrical distribution and progression of the waves in the hair is 10 effected.

The layer 23 is formed from felt or other suitable material and has slits 24 projecting inwardly, these slits being extended at right angles to each other and crossing so that a central opening 15 is formed in the layer 23, which is placed in the cup-shaped member 13 in embracing relation to the rod 12 and the hair wound therein. This layer 23 serves as a sealing gasket and its purpose will appear hereinafter.

20 In order to wind the hair about the rod 12 I provide a winding device consisting of a metal plate doubled upon itself to provide the overlying portions 29 and 30 which embrace and securely grip the rod 12. Each of these doubled 25 over portions is provided at its edge with knuckles 31 and 32 in each of which is positioned a wire 33 and 34 respectively which are formed into a gripping hook 35. The wisp of hair is engaged by the hook 35 and upon a rotation of this hook 30 about the rod 12 the hair is wound firmly around the rod 12. The lower edge 36 of these doubled over members 29 and 30 is inclined so that as the wisp of hair is wound upon the rod 12 the winding member will, through engagement of the 35 inclined surface 36 with the wisp of hair wound on the rod, travel outwardly and thus a uniform winding of the wisp upon the rod is effected.

After the wisp of hair has been wound upon the rod 12 it is covered with the layers 37 of absorbent pads or cloth saturated with the liquid which it is desired to use to produce, in co-operation with the heat, the permanent curl or wave. In carrying out the operation a heating element 38 provided with the insulating sheath or apron 45 39 is used. When the heat is applied, the liquid carried by the pads 37 is vaporized and turned into steam. It is quite necessary that none of this steam be permitted to pass downwardly into engagement with the scalp and it is also quite desirable that none of the condensate may reach 50 the scalp while in a hot condition. To this end the layer 23 serves to function in conjunction with a receptacle forming sleeve 25 which is positioned in concentric relation to the rod 12, as shown in Fig. 3. This sleeve 25 is provided at 55 one end with the outwardly projecting flange 26 having at one point the nose or projection 27. In assembly, the sleeve is placed in position by turning the same until the nose 27 is in alignment 60 with the opening 15 whereupon the flange 26 may be pressed firmly into engagement with the layer 23 which serves as a sealing gasket or washer. A rotation of the sleeve relatively to the member 13 will lock these parts together through the engagement of the nose or projection 27 beneath 65 the flange 14. In this way I provide a tight seal by pressing the layer 23 firmly between the base of the cup-shaped member 13 and the flange 26 so that passage of liquid or steam downwardly 70 into engagement with the scalp is prevented.

The device is one which is compact and very easily and quickly assembled even by an unskilled person. Even with unskilled labor the device may be used without danger of burning the scalp as 75 it is impossible for leakage to occur, the seal re-

ferred to being sufficiently tight for all purposes. The device may also be used with any type of curling machine and the winding member serves to eliminate all necessity of tying the hair on the prong. By having the winding member formed from the pair of doubled over resilient parts 29 and 30 the winding member may be used on curling rods of different size and dimensions. In this way I have provided a curling rod assembly which is adapted for universal use which is effective of a higher grade work than can be accomplished with curling rods now in use and which is absolutely safe so far as burning of the scalp is concerned.

80 While I have illustrated and described the preferred form of my invention, I do not wish to limit myself to the precise details of structure shown, but desire to avail myself of such variations and modifications as may come within the scope of the appended claims.

90 Having thus described my invention, what I claim as new and desire to secure by Letters Patent is:

1. In combination: a curling rod; a cup-shaped member mounted on said curling rod and having 100 a hair receiving opening extended inwardly from its periphery and provided with an upstanding peripheral flange inclined inwardly toward said rod; a co-operating cup-shaped member adapted for snapping over said first mentioned cup-shaped 105 member and, when snapped thereon, rotatable relatively thereto.

2. In combination: a curling rod; a cup-shaped disc on one end of said curling rod and having 110 a hair receiving opening projecting inwardly from its periphery, said disc being provided at its periphery with an upwardly directed flange inclined inwardly of said rod; a stop member projecting outwardly from the base of said cup-shaped member; a cooperating cup-shaped member 115 adapted for snapping over said first mentioned cup-shaped member and having a hair receiving opening extending inwardly from its periphery and provided on the inner surface of its base with an arcuate groove for reception of said stop member.

3. In combination: a curling rod; a cup-shaped member mounted on the end of said curling rod; a co-operating cup-shaped member rotatable on 125 said first mentioned cup-shaped member, each of said cup-shaped members having a hair receiving opening extending inwardly from its periphery; and means for locking said cup-shaped members in fixed rotative relation to each other.

4. In a device of the class described, comprising: a curling rod; a cup-shaped disc on said curling rod; a sleeve surrounding said rod and extending axially thereof for a portion of its length, said sleeve being spaced from said curling rod; and means for sealing the lower end of said 135 sleeve on the face of said cup-shaped member.

5. In a device of the class described: a curling rod; a cup-shaped disc carried on one end of said curling rod; and a rigid, non-collapsible sleeve projecting axially of said disc in surrounding relation to said rod and forming with said disc a receptacle.

6. In combination: a curling rod; a cup-shaped disc carried by said curling rod; a sleeve embracing said curling rod; a flange projecting radially outwardly from one end of said sleeve and positioned within said disc in engagement with the inner surface of its wall; and a gasket positioned between said sleeve flange and said disc.

7. In combination: a curling rod; a cup-shaped 150

member carried on one end of said curling rod and having its peripheral flange inwardly inclined; a yieldable sealing member engaging the base of said cup-shaped member adjacent its outer edge; a sleeve embracing said curling rod; an outwardly projecting flange on one end of said sleeve engaging within the flange on said cup-shaped member and clamping said sealing member against said cup-shaped member.

5 10 8. In combination, a curling rod; a cup-shaped disc mounted on said curling rod, said rod terminating at the end attached to the cup-shaped

member inwardly of the outer face of the base thereof, said cup-shaped member having a hair receiving opening formed therein; a cooperating cup-shaped member adapted for snapping over the base of said first mentioned cup-shaped member and having a cooperating hair receiving opening formed therein, said second mentioned cup-shaped member being unattached to said rod and detachable from said first mentioned disc without disturbing the connections of said rod and said first mentioned disc.
